FISHING CREEL

Lloyd G. Le Blanc, 988 Fairview Road, Duluth, Minn.

Filed Apr. 29, 1960, Ser. No. 60,366

Term of patent 3½ years

(Cl. D58—4)

FIG. 1

FIG. 2

FIG. 3

FIG. 4

I claim:

The ornamental design for a fishing creel, as shown.
